THREAD GUIDE

Paul W. Markwood, Enka, and Jackson A. Moore,
Asheville, N. C., assignors to American Enka
Corporation, Enka, N. C., a corporation of Dela-
ware

Application November 15, 1946, Serial No. 709,966

3 Claims. (Cl. 242—157)

1

This invention relates to thread guides and more particularly to thread guides of the type used to damp the vibration of thread before passage thereof through a cylindrical film of treating liquid.

In the preparation of rayon thread for shipment to knitters, it is customary to wind the twisted thread into conical bodies and to apply the finish or lubricant to the thread during this winding operation. The coning is effected by drawing the thread upwardly from a source, such as a bobbin or package, and by laying up succeeding cross-wound courses thereof on a driven take-up device such as a conical support. Between the thread source and the take-up device, the thread is passed across a rotating cylindrical roller which is partially immersed in a lubricating liquid to provide a cylindrical film of lubricating liquid in the path of the thread during the coning operation.

In the oiling of a thread during a coning operation it has been found that the thread in passage over the oiling roller tends to vibrate to such an extent as to cause very uneven application of the oil to the thread. Furthermore, excessive vibration results in tension peaks which in turn cause a large number of end breaks, thereby reducing the quality of the thread produced.

Efforts have been made to overcome the foregoing difficulties but these have, in general, been unsuccessful due to the fact that the means provided for damping the vibration of the thread were either complex in design and hence costly to build, or were simple in design but were not self-threading so that their use resulted in excessive time loss in rethreading in the event of thread breakage.

It is an object of this invention to overcome the foregoing disadvantages and to provide for the damping of thread vibration before and during the passage of thread over an oiling roller and to accomplish the damping with a simple thread guide which is inexpensive to construct and install and which is of the self-threading type.

Other objects and advantages of this invention will be apparent upon consideration of the following detailed description of a preferred embodiment thereof in connection with the annexed drawings wherein:

Figure 1 is a diagrammatic view in elevation of a portion of a typical coning machine showing the vibration damping thread guide of the present invention in operative association therewith;

Figure 2 is a top plan view of the vibration

2

damping thread guide of the present invention; Figure 3 is a view in bottom plan view of said guide; and

Figure 4 is a view in side elevation of said guide. Referring now in greater detail to the drawings and particularly to Figure 1, the numeral 10 represents a bobbin constituting a source of thread to be wound into conical form, the bobbin being mounted on a spindle extending upwardly from a platform 11 at the front of the machine. The thread 12 is drawn upwardly from the bobbin by a rotating spindle 13 carrying thereon a cone support 14. Between the bobbin 10 and the cone support 14, the thread is passed through a pigtail guide 15 attached to the frame 16 of the machine, through a guide 17, constructed in accordance with the teachings of the present invention and illustrated more fully in Figures 2, 3 and 4 and finally through a pigtail guide 18. Between the guides 17 and 18 the thread is passed generally tangentially over a cylindrical emulsion roller 19 mounted for rotation on a horizontal shaft and dipping in a trough 20 containing a lubricating liquid which is to be applied to the thread.

Since the shaft 13 rotates at a constant speed throughout the winding period and since the body of thread builds upon the cone support 14, it is apparent that the thread take-up speed increases progressively throughout the winding period. This causes the thread to move more rapidly across the emulsion roller 19 and to prevent this increase in speed from varying the amount of oil applied to the thread, the guide 18 is mounted for lateral movement on a bracket 18a and is automatically laterally shifted to increase the length of the thread path over the roller 19 as the cone increases in diameter and the take-up speed increases. Since the mode of driving the spindle 13, the operation of the bracket 18a and the mode of driving roller 19 are all well known and form no part of the present invention, they are not described in detail herein.

To prevent vibration of the thread in its passage across the roller 19, the guide 17 is employed. This guide comprises three vertically spaced bars 21, 22 and 23 formed from a single piece of heavy wire or the like. One end of the wire is threaded at 24 to constitute a point of attachment to the machine. Immediately adjacent the threaded portion 24, the wire is bent in an oval loop 25 to define a crossbar 26 which lies above the uppermost bar 21 of the three vertically spaced bars. From the end of the oval loop 25 the wire material continues in the plane

and direction of the threaded end 24 to define the uppermost bar 21. At the end of the bar 21 remote from crossbar 26 the wire is bent to the left, as viewed in Figure 2, then vertically down, and then to the horizontal again to define a loop 27 comprised of section 27a in the plane of bar 21, section 27b in the plane of the bar 23 and vertical section 27c therebetween. The wire continues from the section 27b of the loop 27 to define in the same horizontal plane a loop 28 and the bar 23, the former being provided to prevent displacement of the thread in a direction outwardly from the machine. The wire material at the inner or machine side of the bar 23 is bent upwardly in a loop 29 leading to the intermediate bar 22. The intermediate bar 22 ends in an angular projection at 30. The projection at 30 lies about 90° away from the loop 27 and it is apparent that such construction renders the guide 17 very easy to thread up.

The guide is attached to the front of a coning machine by mounting it on a bracket 31 having a hole therein for the reception of the threaded portion 24 of the guide 17. By the use of nuts (not shown) on either side of the bracket, the thread guide may be mounted in various positions of adjustment with respect to the bracket 31, that is, either spaced relatively far out from the bracket or relatively close to it. By these adjustments, it is possible to accurately adjust the thread contact against the emulsion cylinder 19 and to cause the thread to bear against the crossbar 26.

Referring again to Figure 1 it is seen that threading-up the machine requires first the establishment of an unguided thread from bobbin 10 to cone support 14. Once this is established the thread is moved laterally into the pigtail guides 15 and 18 which are, of course, self-threading.

The guide 17 is threaded-up by passing the thread between the loops 25 and 28 and to the right of bars 23, 22 and 21, as they are viewed in Figure 2. A loop is then pulled in the thread between the bars 21 and 23. This loop is released into the mouth of the notch defined between the wire loop 27 of the guide 17 and the projection 30 thereof. Upon release of the thread loop at this point it is pulled out by the thread tension and the thread is guided in a tortuous passageway to the right of bars 21 and 23 and to the left of bar 22 and confined between crossbar 26 in one direction and loop 28 in the other. It has been found that the thread when confined in the guide 17, as indicated above, does not vibrate in its passage across the oiling roller 19. Furthermore, threading-up is extremely simple and slack thread can be removed during starting of the coning spindle 13 by pulling the end forward above the guide. The

loop 28 prevents the thread from disengaging itself from the guide.

What is claimed is:

1. A thread guide comprising three vertically spaced bars, each including a straight thread guiding portion extending across the direction of thread travel and outwardly from a support, said thread guiding portions all lying in substantially the same vertical plane, the upper and lower of said bars coacting with the middle bar to define a mouth facing outwardly of the support for the reception of a thread loop so as to render the guide self-threading, and a crossbar above the topmost of said spaced bars and in the thread path.

2. A thread guide comprising three vertically spaced, generally horizontal bars, each including a straight thread guiding portion, said portions all lying in substantially the same vertical plane and together defining a tortuous thread path and means constituting a part of said thread guide for restraining a thread against excessive movement in a plane parallel to said bars, said means comprising a loop integral with the uppermost bar and a loop integral with the lowermost bar, said loops lying at opposite ends of the respective bars.

3. An adjustable thread guide comprised of a single length of material bent to define three vertically spaced, generally horizontal bars, each including a straight thread guiding portion, said portions all lying in substantially the same vertical plane and together defining a tortuous thread path, said single length of material also defining two loops for limiting movement of a thread in a plane parallel to the bars, one of said loops being integral with the uppermost bar and the other being integral with the lowermost bar, the lowermost bar being supported from the uppermost bar and the intermediate bar being supported from the lowermost bar, the connection between said uppermost and lowermost bars defining with an end of the intermediate bar a notch facing outwardly from the machine to facilitate threading-up of the guide.
